UNITED STATES PATENT OFFICE.

HARRY E. CARY AND THOMAS T. McGUIRE, OF OAKLAND, CALIFORNIA.

DIRIGIBLE HEADLIGHT.

1,417,497.

Specification of Letters Patent. Patented May 30, 1922.

Application filed January 29, 1919. Serial No. 273,813.

To all whom it may concern:

Be it known that we, HARRY E. CARY and THOMAS T. McGUIRE, citizens of the United States, residing at Oakland, in the county of Alameda and State of California, have invented certain new and useful Improvements in Dirigible Headlights, of which the following is a specification.

This invention relates to illumination, and 10 more especially to dirigible light supports which are automatic; and the object of the same is to produce a structure of this type wherein one lamp will be turned aside when the course of the machine is altered and the 15 other will remain stationary.

Another object is to adapt the attachment to machines of various types, and to fasten the operating mechanism to the connecting rods at either side.

20 Another object is to provide means for holding one lamp quite steady while the other is turned.

Yet other objects will appear in the following specification and claim and attention 25 is invited to the drawings wherein—

Figure 1 is a front elevation of this attachment complete.

Figure 2 is a horizontal sectional view of the device, taken on the line 2—2 of Figure 1.

Figure 3 is a right hand end elevation.

Figure 4 is an enlarged plan view with the caps of the gear housings removed.

Figure 5 is a vertical section on the line 35 5—5 of Fig. 4.

Figure 6 is a side elevation of one gear housing with its cap in section, and

Figure 7 is a vertical section on the line 40 7—7 of Fig. 6.

In the drawings, the letter F designates the frame of the automobile and R the rod which connects the two steering knuckles. These knuckles sometimes project to the rear and sometimes to the front and therefore the rods R may move one way or the other when the wheels are turned to the right, but my attachment makes provision for this difference in structure. The letters L designate the lamps mounted in stands S as usual. No novelty is claimed for the parts thus far described.

Attached to each frame bar is a bracket 1 which supports an upright gear housing 2 and a removable cover or cap 3 to enclose the gears yet to be described. Journalized in

the housing is a shaft 4 which depends to a point below the frame F, and connected at 5 to the shaft is an arm 6 herein shown as leading forward. A link 7 has ball and socket joints at its extremities one of which 60 connects with said arm and the other with an arm 8 leading forward from the connecting rod R, to which latter the arm is rigidly connected at the point 9 as by means of a clip best seen in Figure 3. It follows 65 that when the connecting rod is moved the arm 8 moves with it and the link 7 causes the arm 6 to swing so that the shaft 4 is oscillated in its bearing within the housing. If the connecting rod is in rear of the front 70 axle, the oscillation will be in one direction, whereas if the connecting rod is in front of the front axle the oscillation will be in the other direction, unless the shaft 4 be turned so that its arm 6 shall project to the rear. 75 In that case, the length of the arm 6 and the arm 8 will be changed, but the link 7 and its ball-and-socket joint will yet be employed.

The lamp standard S is rotatably mounted 80 in the forward part of the housing 2, and carries at its lower end a nut 10 above which is a spring washer 11. A similar nut 12 and spring washer 13 are mounted on the rock shaft 4, and by this means both 85 shafts are drawn downward within the housing, and the expansion of the spring washers is sufficient to set up some little friction or resistance against the rotation of the shaft. Fast on the upper end of the 90 shaft 4 is a gear 14 meshing with teeth 15 constituting a rack along the rear edge of a bar 16 which extends across the machine to the opposite lamp and this bar by preference has a turn buckle 17 within its length 95 or other means for adjusting it when desired. Guide blocks 18 are formed within the housing and between these the bar reciprocates as the power gear 14 moves it in one direction or the other. In Figure 4, 100 what would be the right hand gear is connected with the rod R and moved thereby, and therefore, the other gear apparently is simply an idler. But it will be clear that if the arm 6 were attached to the lower end 105 of the shaft 4 of what would then be the left hand gear, as is desirable with some makes of machines, then the right hand gear would become an idler. Accordingly, we prefer to have gears at both sides or in both 110

housings, so that the connecting of the link with the rod R may be left to the purchaser who applies the attachment to the machine.

On the standard S in each housing is mounted a mutilated gear 24, its flattened side or chord 23 engaging the front edge of the bar 16 where the same is smooth, while its teeth engage teeth 25 on the bar at the end thereof. A guide block 28 is also provided for engagement by the smooth portion of the front edge of the bar, but it may be wise to omit the guide block in front of the bar and at the outside of the housing.

With the preferred construction, the parts having been properly applied, the action is as follows: As soon as the operator turns the steering wheel and moves the connecting rod R, the arm 8 moves with it and the link 7 causes a corresponding and simultaneous movement of the arm 6. This turns the power gear in one direction or the other and reciprocates the bar 16 and turns the other gear. The smooth portion of the front edge of the bar slides along the chord 23 in both mutilated gears until the teeth 25 at the outer end of the bar which is being drawn inward engage the teeth of one of these mutilated gears. The latter is now turned, and accordingly the lamp standard S at that side of the machine is turned and the lamp L is caused to direct its rays to one side. Meanwhile the smooth portion of the bar 16 at the other side of the machine slides over the chord 23, and the mutilated gear there is not turned. Therefore, the lamp at that side of the machine continues to direct its rays straight ahead. The result is that the driver has one lamp directly ahead and the other throwing its rays in the direction in which he is about to turn. Having turned and straightened out on his course, the parts are restored to their original position. Adjustment of the length of the bar 16 by means of the turn buckle 17 or other device employed, will cause the inner ends of the front tooth racks to approach or recede from the mutilated gears, and therefore result in the action of these mutilated gears earlier or later as is desired. It has been suggested above how the parts might be set if preferred so that the arm 6 projects to

the rear of the shaft 4 for connection with the connecting bar R through the link mechanism described. Also, it will be clear that by removing the pin 5 the arm 6 can be attached to the lower end of the other shaft 4 from that illustrated in the drawings. Therefore, the purchaser has considerable latitude in the application of this device or attachment, and can readily apply it to his machine.

The foregoing description and the drawings have reference to what may be considered the preferred, or approved form of our invention. It is to be understood that we may make such changes in construction and arrangement and combination of parts, materials, dimensions, et cetera, as may prove expedient and fall within the scope of the appended claim.

Having thus fully described our invention, what we claim as new and desire to secure by Letters Patent is:—

In combination with a frame, brackets and gear housing carried thereby secured to the frame, a steering apparatus, a rotatable shaft in each of the gear housings operable by the steering apparatus, a rotatable lamp standard within each of said housings, a toothed gear and mutilated gear secured on the upper ends of the respective shafts and standards of each housing, a transversely extending rack bar operable therewith and in mesh with said gears, each of said mutilated gears having a flattened side adapted to normally maintain the same out of engagement with the rack bars, whereby the mutilated gears will be caused to rotate as the said rack bar is moved in one direction for independently rotating the lamp standards upon opposite sides of the frame at selected time, and means co-operating with said steering apparatus and said rack bar for automatically shifting the same as said steering apparatus is operated.

In testimony whereof we affix our signatures in presence of two witnesses.

HARRY E. CARY,
THOMAS T. McGUIRE.
